UNITED STATES PATENT OFFICE.

ELISHA L. BURTON, OF THEALKA, KENTUCKY, ASSIGNOR OF ONE-HALF TO CHRISTIAN C. HENKEL, OF PAINTSVILLE, KENTUCKY.

AUTOMATIC SWITCH.

1,301,100.

Specification of Letters Patent. Patented Apr. 22, 1919.

Application filed October 19, 1918. Serial No. 258,865.

To all whom it may concern:

Be it known that I, ELISHA L. BURTON, a citizen of the United States, residing at Thealka, in the county of Johnson and State 5 of Kentucky, have invented certain new and useful Improvements in Automatic Switches, of which the following is a specification, reference being had to the accompanying drawings.

10 This invention relates to an improved automatic switch, and has for its primary object to provide switch actuating means primarily designed for mine railways, whereby the switch is automatically operated by trip means on the mine car locomotive so that the locomotive will be directed upon the side track while the loaded cars will continue to travel upon the graded track leading to the car tipple.

15 It is also another object of my invention to provide an automatic switch operating mechanism which, after the switch has been closed by one locomotive, will discharge the loaded cars hauled thereby to the tipple and subsequently be successively actuated by a 20 second locomotive operating upon the track to shunt the latter upon the side track and then close the main track for the loaded cars.

25 It is also another object of my invention to provide an automatic switch operating mechanism as above characterized which 30 consists of relatively few parts that may be readily installed in mine railway systems now in common use without necessitating 35 any radical alterations therein.

35 It is also one of the detail objects of the invention to provide means for insuring the full throw of the switch points and to guard against the possibility of accidental or casual shifting movement of the points.

40 And it is a further general object of the invention to provide a switch throwing mechanism, the several parts of which are very durably constructed, not liable to get 45 out of order, and which will be efficient and reliable in practical operation.

45 With the above and other objects in view, the invention consists in the improved construction, combination and relative arrangement of the several parts as will be herein- 50 after more fully described, subsequently claimed and illustrated in the accompanying drawings in which similar reference charac-

ters designate corresponding parts throughout the several views, and wherein:—

55

Figure 1 is a perspective view showing the relative positions of the parts when the main track for the loaded cars is open;

Fig. 2 is a plan view showing the mechanism after it has been actuated by the trip device on the locomotive, the main track being closed;

Fig. 3 is a section taken on the line 3—3 of Fig. 2;

Fig. 4 is an enlarged elevation of certain parts of the mechanism; and

Fig. 5 is a detail perspective view of the trip device.

Referring in detail to the drawings, 5 designates the main track which is properly 70 graded and over which the loaded cars travel to the car tipple where the contents of the cars are discharged. 6 designates the side track upon which the empty cars are returned, and 7 the movable switch points. 75 These switch points are connected by the bar 8 extending between adjacent supporting ties and are adapted to be actuated by my improved mechanism, to be later described in detail, whereby the mine car locomotive may be automatically shunted from the main track upon the side track, while the loaded cars pass on over the main track to the tipple.

At one side of the track, spaced bearing 85 members 10 are suitably secured upon the rail ties, and a rock shaft 11 is mounted in said bearing members. This shaft at its

90

opposite ends is formed with the crank arms 12 and 13 respectively which extend substantially at right angles relative to each other. Upon a bolt 14 fixed in the upper end of one of the bearing members 10, the trip device 15 is pivotally mounted, said device having arms 16 and 17 which extend substantially at right angles to each other. At one side of the pivot 14, this trip device is connected by means of the link 18 to the arm 12 of the rock shaft. A rod 19 is disposed 95 in parallel relation to the trip device 15 on one side thereof and is fixed at its ends thereto. One end of a coil spring 20 is slidably engaged upon said rod, the other end of the spring being secured to the rock shaft 11.

100

At a point in spaced relation to the

105

trip device, a standard 21 is mounted, and upon a horizontally disposed bar 22, fixed at one of its ends to said standard, the rock shaft 23 is mounted. This shaft is provided upon one end with a crank arm 24 and also has a crank 25 formed on its opposite end. This latter crank is connected by a link 26 to the bar 8 which connects the movable switch points to each other upon one end of a bolt 27 which is mounted in the upper end of the standard 21, an arm 28 is engaged, said arm being fixed to a metal strap 29 which is secured to a lever 30, said lever being mounted upon the opposite end of the bolt 27. One end of the arm 28 is connected by a link bar 31 to the crank arm 24 of the shaft 23 and the lower end of the lever 30 is operatively connected by a rod 32 to the crank arm 13 on one end of the rock shaft 11. The lever 30 is also connected by means of a rod 33 to a crank arm 35 on one end of a rock shaft 34, which is mounted in spaced bearing standards 36. To the other end of the rock shaft 34, an arm 37 is fixed and is operatively connected by the link 38 to a trip member 39 which is pivoted, as at 40, upon the upper end of one of the standards 36.

In the operation of the mechanism as above described, assuming that the switch points are in the positions shown in Fig. 1, so that the locomotive hauling the cars may move from the main track upon the side track 6, when the rear wheels of the locomotive have passed the switch points, a tappet rod or trip member 41 which is mounted for sliding movement in a sleeve 42 fixed upon the rear end of the locomotive, strikes the arm 17 of the trip device 15 and oscillates said device upon its pivot 14 from the position shown in Fig. 1 to the position shown in Fig. 4 of the drawings. In the movement of the trip device to the latter position, the shaft 11 is rocked and through the medium of the rod 32, lever 30, and the connection between said lever and the shaft 23, said shaft is rotated and the link bar 26 moved to throw the switch points to the position seen in Fig. 2. The loaded cars which have been uncoupled from the locomotive may thus continue their movement upon the main track to the tipple where the contents of the cars are discharged. When the trip device 15 is actuated as above explained, the end of the spring 20 slides freely on the rod 19 to the opposite end of said rod and assumes an angular position upon the relatively opposite side of the shaft 11 from that shown in Fig. 1, so that the trip member is held against the possibility of casual or accidental rocking movement upon its pivot. The spring 20 thus effectively serves to maintain the switch points in the positions to which they have been moved. After the

locomotive has been coupled to the empty cars returned on the track 6, in its reverse movement, the tappet member 41 first strikes the arm 16 of the trip member before the wheels reach the switch points. Thus, the movement of said trip member is reversed and the switch points again moved to the position seen in Fig. 1 so that the locomotive may enter upon the main track.

In case two or more locomotives are used upon the same track after the first has actuated the switch and moved upon the side track 6 as above explained, a following or second locomotive will also be shunted upon the track 6 as the tappet member 41 carried by the latter locomotive will strike the trip member 39 and return the parts of the mechanism and the switch points to the position seen in Fig. 1 and after moving upon the side track, said tappet member will then strike the arm 17 of the trip member 15 and move the switch points to again close the main track as above explained.

From the foregoing description, taken in connection with the accompanying drawings, the construction, manner of operation and several advantages of my improved automatic switch mechanism will be clearly and fully understood. I have found the device in practical use to be highly efficient and reliable in its operation, particularly in connection with mine track systems. It is apparent, however, that with certain obvious mechanical modifications, the mechanism is likewise applicable to ordinary railroad track systems. The device is almost instantaneous in its action so that even when the locomotive is traveling at very high speed, the full throw of the switch points is assured. Of course, when occasion requires, the mechanism may be manually operated by simply shifting the lever 30. In case only a single hauling locomotive is to be used upon the track, the trip member 39 and its connections with the lever may be removed. When necessary, these parts can be easily and quickly arranged in operative position at the side of the track and connected to the operating lever.

I have herein disclosed what I have found to be a very satisfactory and reliable form, construction and arrangement of the several parts but it is to be understood that the mechanism is susceptible of many modifications therein and I, accordingly, reserve the privilege of resorting to all such legitimate changes as may be fairly embodied within the spirit and scope of the invention as claimed.

I claim:

1. In combination with movable switch points, actuating mechanism therefor, including a pivotally mounted tripping member adapted to be engaged and actuated by means on a locomotive, means operatively

connecting the tripping member to the movable switch points, and means for yieldingly holding the tripping member against casual pivotal movement including a transversely 5 extending rod mounted upon the tripping member, and a contractile spring fixed at its lower end and at its upper end slidingly engaged with said rod.

2. In combination with movable switch 10 points, actuating mechanism therefor including a pivotally mounted trip member adapted to be engaged and actuated by means on a locomotive, a rock shaft, means operatively connecting the rock shaft to the 15 movable switch points, connecting means between the rock shaft and said trip member, and a spring to yieldingly hold the trip member against pivotal movement in each direction and having a shiftable connection 20 at one of its ends with said trip member.

3. In combination with movable switch points, actuating mechanism therefor including a pivotally mounted trip member, a rock shaft, an operative connection between 25 the rock shaft and the trip member, a manually operable lever, means operatively connecting the lever to said rock shaft, a second rock shaft, connecting means between one end of the latter rock shaft and 30 the switch points, and an operative connection between the other end of said shaft and said lever.

4. In combination with movable switch points, automatic operating means therefor 35 including spaced trip members adapted to be engaged and actuated by means on a locomotive, one of said trip members having spaced parts for engagement by said means in the movement of the locomotive in either 40 direction, a rock shaft arranged between the trip members, an operative connection

between the rock shaft and the switch points, and means operatively connecting each of the trip members to said rock shaft.

5. In combination with movable switch 45 points, automatic operating means therefor including spaced trip members adapted to be engaged and actuated by means on a locomotive, one of said trip members having spaced parts for engagement by said means 50 in the movement of the locomotive in either direction, a rock shaft arranged between the trip members, an operative connection between the rock shaft and the switch points, means operatively connecting each 55 of the trip members to said rock shaft, and means connected to one of said trip members to yieldingly hold the same against pivotal movement and thereby retain the switch points in the positions to which they 60 have been moved.

6. In combination with movable switch points, actuating mechanism therefor including a pivotally mounted trip member, a rock shaft, means operatively connecting 65 one end of the rock shaft to the switch points, operating connections between the other end of said shaft and the trip member, a rod fixed to one side of the trip member and extending upon each side of its 70 pivot, and a coil spring having a shiftable connection at one of its ends to said rod to hold the trip member against casual pivotal movement and retain the switch points in the positions to which they have 75 been moved.

In testimony whereof I hereunto affix my signature in the presence of two witnesses.

ELISHA L. BURTON.
